UNITED STATES PATENT OFFICE

139,495

DESIGN FOR A PERFUME CONTAINER

George Bennett, New York, N. Y., assignor to Pinaud Incorporated, New York, N. Y., a corporation of New York

Application July 28, 1944, Serial No. 114,602

Term of patent 14 years

(Cl. D86—10)

To all whom it may concern:

Be it known that I, George Bennett, a Russian citizen and a resident of the city, county, and State of New York, have invented a new,
original, and ornamental Design for a Perfume Container, of which the following is a specification, reference being had to the accompanying drawing, forming a part thereof.

This application is a continuation-in-part of my application, Serial No. D. 110,871, filed August 9, 1943.

Fig. 1 is a perspective view of a perfume container in closed position showing my new design; and

Fig. 2 is a separated view in perspective of the two parts comprising the container shown in Figure 1.

The lining on the drawing represents contrasting color.

I claim:

The ornamental design for a perfume container, as shown and described.

GEORGE BENNETT.
